UNITED STATES PATENT OFFICE.

JOHN DEWRANCE, OF SOUTHWARK, ENGLAND.

STOP-VALVE.

1,137,194.

Specification of Letters Patent. Patented Apr. 27, 1915.

Application filed April 18, 1914. Serial No. 832,945.

To all whom it may concern:

Be it known that I, JOHN DEWRANCE, a subject of the King of Great Britain and Ireland, residing at 165 Great Dover street, 5 Southwark, in the county of Surrey, England, have invented new and useful Improvements in Stop-Valves, of which the following is a specification.

This invention relates to stop-valves of 10 the "sliding gate" type, such as commonly employed for controlling steam passages and water ways of considerable size and where-in the gate or shutter partakes of a sliding movement between parallel seatings arranged on either side thereof.

In stop-valves of the kind above referred to, the shutter commonly comprises two disks between which is arranged a spiral or other spring which serves to maintain the 20 opposite faces of the valve in close contact with the seatings which respectively terminate the inlet and outlet passages formed in the valve-casing when the valve is opened and the greater portion of the shutter is 25 withdrawn from between the said seatings, it is necessary to prevent the two disks separating under the influence of the intervening springs; and my present invention relates to improved means for accomplishing this 30 object, as also for facilitating the assemblage of the parts, and to afford increased safety during dismounting, the valve being securely attached to the spindle whereby it is 35 operated.

In the accompanying drawings is represented a stop-valve constructed according to my improved method; Figure 1 being a transverse section, Fig. 2 a longitudinal section and Fig. 3 a sectional plan view on the 40 line $\alpha-\alpha$ in Fig. 1. Fig. 2^a shows on an enlarged scale the valve facing embodied in Fig. 2.

The shutter comprises two disks A A having between them a spiral spring B. In 45 the periphery of each of the disks is formed a groove α , and concentrically with the disks is arranged a ring C, the lower portion of which is formed with two snugs c which project radially inward; these snugs being 50 adapted to engage in the circular grooves α , α , formed in the two disks A A. The lower extremity of the hollow spindle D whereby the shutter is raised and lowered, is similarly provided with two snugs d d 55 adapted to engage in the upper portions of the circular grooves α α formed in the two

disks. The ring C is formed with a head c^2 beneath which is inserted horizontally a U-shaped keep E; the latter engaging with the hollow spindle D by means of two lateral recesses or flats d' d' formed for its reception. The U-shaped keep E is retained in position by means of a pin e which passes transversely through the extremities of its legs. The hollow spindle is designed in such 60 a manner that its sectional area suffers no reduction at the part where the lateral flats d' d' are formed for the reception of the U-shaped keep.

The working face of each of the valve-disks is provided with a facing α' of incor- 70 rosible metal. For the purpose of securing such a facing in position, I form a circular groove α^2 in the face of the disk, the inner edge of the said groove terminating 75 in a thin radially projecting lip α^3 . The back of the facing is formed with an annular projection α^4 adapted to fit the said groove α^2 and terminates in a centrally projecting rib α^5 located immediately behind the 80 thin lip α^3 of the disk. The facing α' having been placed in position, the thin lip α^3 on the disk is, with the aid of calking tools, turned down over the rib α^5 on the facing, 85 whereupon the facing α' is securely connected together to the disk A.

The co-efficient of expansion of the incor- 90 rosible metal facing is somewhat greater than that of the steel disk. Prior to inserting the annular projection α^4 of the facing 95 in the circular groove α^2 of the disk, I apply to the outer circumference of the former a strip of stout paper or like combustible material. The mounting of the facing in the disk is then proceeded with in the manner described; the presence of the paper strip preventing metal-to-metal contact between the outer circumference of the annular pro- 100 jection α^4 and the outer circumference of the groove α^2 . When, however, the valve is em- 105 ployed with superheated steam, the paper or like strip is burned away, and the space previously occupied by it is rendered available for differential expansion on the part of the facing ring α' .

A stop-valve constructed in the manner hereinbefore described presents the important advantage that the disk A A forming the valve faces are free to rotate about the axis of the ring C whereon they are mounted; it being well known that constant change 110 in the relative positions of working surfaces

has the effect of equally distributing wear and insuring long continued efficiency.

I claim:

1. In a stop-valve of the sliding-gate or shutter type, a shutter consisting of two spring-supported disks mounted in a ring wherein they are free to rotate, each of said disks engaging at one side of its periphery with said ring by means of a snug which 10 enters a groove on the disk, while at the other side a snug formed upon the extremity of a non-rotatable operating spindle engages in the same groove.
2. In a stop-valve of the sliding-gate or

shutter type, the combination with a pair of 15 circumferentially grooved valve-disks, of a ring formed or provided at one side of its periphery with snugs adapted to engage in the grooves in the said valve-disks, and at the other side with a head adapted to engage with a non-rotatable operating spindle formed at its inner extremity with snugs adapted to engage in the grooves on the valve-disks.

JOHN DEWRANCE.
